United States Patent Office

Des. 192,502
Patented Apr. 3, 1962

192,502

BARBER CHAIR OR SIMILAR ARTICLE

Nobuhiro Yoshikawa, Brooklyn, N.Y., assignor to Takara
Company, New York, Inc., Brooklyn, N.Y., a corporation of New York

Filed Sept. 13, 1961, Ser. No. 66,712

Term of patent 14 years

(Cl. D15—3)

FIG. 1

FIG. 1 is a top plan view of a barber chair embodying the invention;

FIG. 2 is a front perspective view thereof;

FIG. 3 is a side perspective view thereof; and

FIG. 4 is a rear perspective view thereof.

I claim:

The ornamental design for a barber chair or similar article, substantially as shown.
